BOAT ANCHOR

William F. Hebrank, Highland, Ill.

Application April 1, 1959, Serial No. 55,298

Term of patent 14 years

(Cl. D71—1)

FIG. 1.

FIG. 3.

FIG. 2.

Fig. 1 is a top plan view of a boat anchor, showing my new design;

Fig. 2 is a front elevational view of the anchor shown in Fig. 1. The opposite rear view is the same except for the omission of the screw fastener, and

Fig. 3 is an elevational view of the anchor shown in Fig. 1 as seen at angle of 45 degrees from the front.

I claim:

The ornamental design for a boat anchor, substantially as shown and described.
